UNITED STATES PATENT OFFICE.

JOHN F. TRITLE, OF SCHENECTADY, NEW YORK, ASSIGNOR TO GENERAL ELECTRIC COMPANY, A CORPORATION OF NEW YORK.

SYSTEM OF CONTROL FOR ELECTRIC MOTORS.

1,160,674.

Specification of Letters Patent.

Patented Nov. 16, 1915.

Application filed December 26, 1913. Serial No. 808,701.

To all whom it may concern:

Be it known that I, JOHN F. TRITLE, a citizen of the United States, residing at Schenectady, county of Schenectady, State 5 of New York, have invented certain new and useful Improvements in Systems of Control for Electric Motors, of which the following is a specification.

This invention relates to the control of 10 electric motors, and especially to a plurality of railway motors.

The object of the invention is to provide a semi-automatic system for controlling a railway car equipment comprising four 15 motors, said system requiring a controller having but three positions, one for the series connection of said motors, one for connecting them in series parallel, and one for their parallel connection. For each position of 20 the controller, three successive changes occur in the circuit connections due to the automatic features of the system, as will hereinafter fully appear.

In the accompanying drawings, Figures 1 25 to 9 inclusive are diagrams showing the successive circuit connections in passing through the nine changes which occur in one acceleration, and Fig. 10 is a diagram of the entire system.

30 In this last figure heavy lines are used to indicate power leads and light lines the control circuits. The line current comes in through the collecting device t and energizes the finger t' of the controller and also 35 the switch arm of the line contactor L . The current flowing to the four motors A, B, C and D is controlled by eight electromagnetic switches or contactors 11 to 18. The last six are of any simple construction, those shown 40 conventionally in the drawing having a single solenoid winding acting upon a movable core attached to the switch arm. The first two contactors, however, are of a type which do not respond to a heavy current but close 45 only when said current has been reduced to a predetermined strength. This contactor is not of my invention, and is only conventionally shown in Fig. 10. It has an electromagnet provided with a winding 19 in 50 series with the line, a two-armed pivoted armature having two air gaps 20, 21, and a magnetic shunt 22, these parts being so adjusted that a heavy current will magnetize the core of the electromagnet to such an extent that the longer arm 23 of the armature

holds this element stationary. But when the current is cut down, the magnetic shunt carries so much larger proportion of the flux that the flux across the air gap at the end of the longer arm of the armature is no 60 longer sufficient to hold said arm against the pull of the flux across the other air gap, and consequently the armature is turned on its pivot and the movable contact 24 carried by said armature is closed upon the stationary 65 contact 25. These contactors will be herein-after referred to as series contactors. The winding 19 of series contactor 11 is in series with a resistor R' and is connected to the switch arm of the contactor 17. The contact 70 24 is also connected to the winding 19 so that when it closes upon contact 25 a shunt is established around the resistor R' . From an intermediate point on the winding of series contactor 11 a lead runs through a second resistor R^2 to the winding of the series contactor 12, and thence to the switch arm of contactor 15. An intermediate point on the winding of series contactor 12 is connected to the switch arm of contactor 13. The contacts of the contactor 12 short circuit the 75 resistor R^2 .

One terminal of motor A is connected to the fixed contact of contactor 13 and the switch arm of contactor 14 whose fixed contact is grounded. Adjacent terminals of motors A and B are connected to the fixed contact of contactor 15. Adjacent terminals of motors B and C are connected to the fixed contact of contactor 17 and the switch 80 arm of contactor 18, whose fixed contact is grounded. The adjacent terminals of motors C and D are connected to the fixed contact of contactor 16; while the other terminal of motor D is grounded. 85

A mechanical interlock 26 between the two series contactors prevents the second one from operating until the first one has closed. Electrical interlocks a to m are arranged in the various control circuits and 90 are operated by the several contactors (except 15) as will hereinafter appear.

The controller has a segment t^2 co-operating with the finger t' and extending across all three positions of said controller. Segment s^2 also covers all three positions and co-operates with finger s' which is connected to the line contactor L , and also through the winding of contactor 13 to a lower contact of the double interlock f . Segment s^2 ex- 105 110

tends across positions II and III and cooperates with finger s' connected to a conductor s which runs to contacts of the single interlocks e and m and the double interlock i ; while segment p^2 occupies position III only and cooperates with finger p' connected by conductor p with an upper contact of double interlock f . The three positions of the controller correspond with the 5 series, series parallel and parallel connections of the motors, the several contactors operating automatically to effect the proper circuit changes when the controller is turned to the position selected.

10 15 The operation is as follows:

Position I, series.—Contactor L and contactor 13 pick up, closing the line upon the resistor R' , part of winding of series contactor 11, resistor R^2 , part of winding of 20 series contactor 12 and the four motors, all in series. As the motors speed up, their counterelectromotive force cuts down the current to a point where series contactor 11 will close and shunt the resistor R' . This 25 increases the current somewhat, so that the motors must attain a higher speed before their counterelectromotive force will be sufficient to weaken the current to a point where the series contactor 12 will close and shunt the resistor R^2 , leaving the motors directly 30 across the line. When contactor 12 closes, contactor 11 will open again because its winding has been shunted by contactor 12. These steps are shown in Figs. 1, 2 and 3. 35 The circuit through the contactor 13 is by way of the lower contacts of double interlocks f and h . Contactor 13 when closed, opens single interlock d in the circuit of contactor 14. Series contactor 11 when 40 closed shifts double interlock a from the upper to the lower of its two pairs of contacts. Series contactor 12 closes both the single interlocks b and c , the latter serving to keep the circuit of contactor 13 closed to 45 irrespective of interlock h .

Position II, series parallel.—Current flows from segment s^2 to finger s' , thence by conductor s and interlock m to contactor 17, and thence by single interlock g to interlock 50 b (closed by the series contactor 12) and interlock a to ground. The energizing of contactor 17 closes the upper pair of contacts in the interlock h and establishes a holding circuit for the contactor 17 through the interlocks h and h . The switch arm of contactor 17 closes a shunt around the motors A and B through the resistor R' and a portion of the winding of contactor 11 in parallel 55 with resistor R^2 , the combination being in series with the remaining portion of the winding of the contactors 11, Fig. 4. The current now has two paths, one through contactors 12 and 13 and the other through the multiple shunt. The small amount of current flowing through this shunt, causes series

contactor 11 to close, (Fig. 5), which de-energizes series contactor 12 and causes it to open. This breaks the holding circuit of contactor 13, and when its switch arm drops the interlock d becomes closed. This energizes contactor 14 because the upper pair of contacts of interlock i were previously closed when contactor 17 was energized. The closing of contactor 14 grounds one terminal of the pair of motors A, B, reversing 70 the direction of current through them and putting them in series parallel with the pair of motors C, D. (Fig. 6).

Position III, parallel.—To go into parallel, the motorman turns the controller to position III, bringing segment p^2 , into contact with finger p' , and energizing conductor p . The previous closing of contactor 14 has closed the upper pair of contacts of the interlock f , so that current can now flow to 85 the contactors 15 and 16. Contactor 15 shunts motor B through resistor R^2 and the winding of series contactor 12 and contactor 16 shunts motor C through resistor R^2 , (Fig. 7). The closing of contactor 16 breaks the 90 holding circuit of contactor 17 at the interlock h , but said circuit is maintained by way of the lower contacts of interlock a which were closed when the series contactor 11 closed in Fig. 5. The small amount of current flowing through the resistor R^2 and the winding of contactor 12 by way of contactor 15 now causes contactor 12 to close (Fig. 8). This short circuits contactor 11 and allows it to open, which breaks the holding circuit of 100 contactor 17 at the interlock a . When the switch arm of contactor 17 drops, it closes the lower contacts of the interlock i , and thereby sends current to the contactor 18 by way of interlocks f and h (upper contacts) and i (lower contacts). When 18 picks up it grounds the adjacent terminals of motors B and C, reversing the current through both of them (Fig. 9). All four motors are now 105 in parallel.

110 It is thus apparent that my invention provides for the successive changes in circuit connections required to place four motors in series, series parallel and parallel, with only three control conductors, three positions on the controller, and two resistors.

115 In accordance with the provisions of the patent statutes, I have described the principle of operation of my invention together with the apparatus which I now consider to represent the best embodiment thereof; but I desire to have it understood that the apparatus shown is only illustrative, and that the invention can be carried out by other means.

120 What I claim as new and desire to secure by Letters Patent of the United States, is:—

1. The method of controlling a plurality of electric motors, which consists in connecting them in series through two resistors and two contactors, automatically shunting the 130

first resistor, and then automatically shunting the first contactor and both resistors.

2. The method of controlling a plurality of electric motors, which consists in connecting them in series with two resistors, and with two contactors responsive to a weakened current only, said contactors closing in succession and each acting when closed to shunt one of said resistors.

10 3. The method of controlling a plurality of electric motors, which consists in connecting them in series through two resistors, and with two contactors responsive to a weakened current only, short circuiting two of 15 said motors by a shunt around one of said resistors and contactors, thereby causing the first contactor to close and send an increased current through the second contactor, which thereupon opens, automatically disconnecting 20 said second contactor from the short circuited pair of motors, and automatically grounding one terminal of said pair and thereby reversing the current through them.

25 4. The method of controlling a plurality of electric motors, which consists in connecting them in series through two resistors and two contactors responsive to a weakened current only, short circuiting two of said motors 30 by a shunt around one of said resistors and contactors, thereby causing the first contactor to close and send an increased current through the second contactor which thereupon opens, automatically disconnecting 35 said second contactor from the short circuited pair of motors, automatically grounding one terminal of said pair, closing two shunts respectively around two of said motors, through the second resistor, one shunt including the second contactor, and thereby 40 weakening the current through the second contactor to such an extent that it closes, and then automatically grounding a point between the two pairs of motors.

45 5. Means for controlling four electric motors, comprising two series contactors re-

sponsive to a weakened current only, a resistor in shunt to the contacts of each contactor, six contactors having switch arms controlling the terminals of said motors and 50 two ground connections, single interlocks actuated by the third, fourth, sixth, seventh and eighth of said contactors, double interlocks controlled by the first, fourth, sixth, and seventh contactors, two single interlocks 55 controlled by the second contactor, a controller having three positions and circuit connections between said controller and said contactors and interlocks.

6. The method of controlling four or more 60 electric motors which consists in connecting them in series with two resistors, short circuiting said resistors in succession, connecting the two resistors in parallel with the two of said motors in series, connecting this lat- 65 ter combination in series with the other two motors, and then short circuiting the first two motors, thereby connecting the other two motors across the line.

7. The method of controlling four or more 70 electric motors which consists in connecting them in series with two resistors, short circuiting said resistors in succession, connecting the two resistors in parallel with the two of said motors in series, connecting this lat- 75 ter combination in series with the other two motors, short circuiting the first two motors thereby connecting the other two motors across the line, opening the short circuit and connecting to ground thereby placing the 80 two groups of motors in series parallel relation, then shunting one of each group of motors with one of said resistors, short circuiting said resistors, then opening the short circuit and connecting to ground thereby 85 placing all the motors in parallel.

In witness whereof, I have hereunto set my hand this 23rd day of December 1913.

JOHN F. TRITLE.
